UNITED STATES PATENT OFFICE.

JAMES A. FLOMERFELT, OF NEW YORK, N. Y.

DESIGN FOR A LINK CUFF-BUTTON.

SPECIFICATION forming part of Design No. 24,092, dated March 12, 1895.

Application filed February 11, 1895. Serial No. 538,041. Term of patent 7 years.

To all whom it may concern:

Be it known that I, JAMES A. FLOMERFELT, a citizen of the United States, residing at the city of New York, county and State of New York, have invented a new and useful Design 5 for a Link Cuff-Button, of which the following is a specification.

Reference is to be had to the accompanying drawings illustrating my design, in which—
10 Figure 1 is a side elevation of a link cuff-button embodying the design, and Fig. 2 is a front view thereof.

The leading feature of my design consists in the rearwardly curved or concaved outline 15 presented to the eye by the intermediate shank portion 1 of the button, in connection with the angular disposition of the flattened-spheroidal heads 2, 3 at opposite ends of the shank, whereby the heads incline toward each 20 other from the rear toward the front of the

button. In other words, the distinctive novelty of the design consists in the rearwardly or inwardly curved or concaved shank 1, as combined with the two angularly disposed flattened-spheroidal heads 2, 3 lying mainly in 25 planes inclined forwardly toward each other.

What I claim is—

The design for a link cuff-button, comprising an inwardly or rearwardly curved or concaved shank portion, and flattened-spheroidal 30 angularly disposed heads at opposite ends of the shank and inclined forwardly toward each other, as set forth.

In testimony whereof I affix my signature in the presence of two witnesses.

JAMES A. FLOMERFELT.
